(57) **CLAIM**

The ornamental design for a post top lighting fixture, as shown and described.

DESCRIPTION

FIG. 1 is a first perspective view of the post top lighting fixture;

FIG. 2 is a second perspective view of the post top lighting fixture;

FIG. 3 is a side view of the post top lighting fixture;

FIG. 4 is an enlarged bottom plan view of the post top lighting fixture; and,

FIG. 5 is a top plan view of the post top lighting fixture. The areas of solid black are a result of drafting technique and do not denote the color black or color contrast.
